UNITED STATES PATENT OFFICE.

JOHN EDWARD CRIGGAL, OF COVENTRY, ENGLAND, ASSIGNOR TO COURTAULDS LIMITED, OF LONDON, ENGLAND.

SQUIRTING-NOZZLE FOR USE IN THE MANUFACTURE OF STRIPS AND THE LIKE FROM VISCOSE AND ANALOGOUS MATTER AND FOR SIMILAR PURPOSES.

1,366,166.

Specification of Letters Patent. Patented Jan. 18, 1921.

Application filed February 4, 1919. Serial No. 274,969.

To all whom it may concern:

Be it known that I, JOHN EDWARD CRIGGAL, a subject of the King of Great Britain, residing at 28 Queen's road, Coventry, in the county of Warwick, England, have invented new and useful Improvements in Squirtng-Nozzles for Use in the Manufacture of Strips and the like from Viscose and Analogous Matter and for Similar Purposes, 10 of which the following is a specification.

The object of this invention is to provide squirting nozzles for use in the manufacture of strips, and the like, from viscose, or analogous matter, and for similar purposes, 15 which nozzles are more economically and accurately manufactured than has hitherto been the case with such nozzles, while they are stronger and not liable to the deformation to which such nozzles as hitherto made 20 have been liable. Such nozzles when made of such expensive metal as platinum have either to be made very thin, or of such thickness as renders them very expensive. When made thin the pressure of the material which 25 is squirted through the nozzle has caused the portion in which the slot is formed to be bulged outward, and consequently the slot in the said portion has been distorted, a further disadvantage being that in such nozzles it is very difficult and expensive to form 30 the slot by perforating the disk which forms the portion in which the slot has to be formed.

According to the present invention the portion in which the slot is, or slots are, made is formed in parts so that the slot, or slots, can be made and finished, or polished, from the side of one, or more, of such parts and be therefore readily and accurately formed in 40 comparatively thick material which therefore can be of a cheap kind, (as compared with platinum for example) provided that it be such as will not be injured by the matter squirted and which will not injure the 45 said matter.

I will describe, with reference to the accompanying drawing, the best manner with which I am acquainted for making a nozzle in accordance with this invention, it being 50 understood that I do not limit myself to the precise details, nor to the precise way herein-after described for carrying out the manufacture of the said nozzles. It is presumed for the sake of description that the nozzle is

to be used in making strips from viscose by 55 squirting it into a setting bath through a single slot in the nozzle.

Figure 1 represents the completed nozzle in perspective. Fig. 2 is a plan of the disk. Fig. 3 is a plan, and Fig. 4 is a vertical section of the nozzle. Fig. 5 is a vertical section of the body part in the course of the manufacture of the nozzle and before the disk (shown in section above it) is put, and secured, in place. 65

The nozzle is made from an alloy of nickel and copper, such, for example, as that known on the market as Monel metal, the portion in which the slot is formed being preferably rolled hard and being of a thickness not 70 liable to be materially distorted under the pressure to which it is subjected by the viscose in squirting. The body part A of the nozzle consists of a tubular portion a^1 with an outward flange a^2 at one end for securing 75 the nozzle in place on the tube of the squirting apparatus and, at the other end, with an inward flange a^3 , a little distance from the said end. A disk B, divided diametrically into two parts, or halves, (marked b^1 and b^2 80 respectively) is provided and, in the straight side of one (b^1) of these half disks, a slot b^3 of the required size is formed by cutting into the half disk from the said straight side, and the said slot is truly shaped and polished 85 and forms one side and the two ends of the slot in the finished nozzle. The remainder of the straight side (marked b^4) of the said half disk and also the straight side b^5 of the second, or companion, half disk are made 90 to truly fit against each other and the part of the straight side of the said second half disk which comes opposite the slot in the first named half disk, when the two half disks are placed together, constitutes the second side of the slot. The said two parts constituting the disk B, are then bored with a suitable number of rivet holes (six are shown at b^6) in a circle corresponding with the part of the disk which, when in place, 100 comes against the inner flange a^3 of the body part of the nozzle. The disk B is then clamped in a lathe and its circumference is turned to truly fit the interior of the body part A above, and upon, the inner flange a^3 , 104 the said body part being preferably also turned truly at the part where the disk is to fit and then, when the disk is in place, rivet

holes a^4 corresponding to those in the disk, B, are drilled in the inward flange a^3 and the disk B is firmly and truly secured in place by riveting the disk and flange together by 5 rivets c while the body part A is supported upon any suitable post.

- Any portion of the body part A which may project beyond the disk, (such as that shown at a^5 in Fig. 5) can then be removed 10 and the edge of the body part is preferably rounded off, as at a^6 , and the disk, or end, and any other desired part, of the nozzle can be plated with any suitable metal, such as gold, for example, if desired. 15 Although I have described the shaping and finishing of the half disks as though each half disk were operated upon separately, it will be understood that several half disks will generally be placed together 20 and be simultaneously subjected to each of the operations described. It will also be understood that, although I have described the nozzle as being provided with but one long slot that any number of such slots can be 25 employed so that one, or more than one, strip, or the like, can be squirted through each nozzle (the disk being then made in as

many parts as may be necessary) and that the slots, or the like, may be of any shape which can be formed in half disks, or two, or more, parts of disks, in the manner hereinbefore explained. 30

What I claim is:—

1. A squirting nozzle for discharging cellulose solution to a setting bath, comprising a divided plate, one part of said plate being recessed at its meeting edge to form wholly therein a discharge opening for the nozzle. 35

2. A squirting nozzle for discharging cellulose solution to a setting bath, comprising a body part having inwardly extending flange means, a divided plate secured to said flange means, one part of said plate being recessed at its meeting edge to form wholly 40 therein a discharge opening for the nozzle. 45

In testimony whereof I have signed my name to this specification in the presence of two subscribing witnesses.

JOHN EDWARD CRIGGAL.
